US0D1022598S

(12) **United States Design Patent** (10) **Patent No.:** **US D1,022,598 S**
(45) **Date of Patent:** **** Apr. 16, 2024**

(54) **BEVERAGE CONTAINER ASSEMBLY**

(71) Applicant: **SPROGO LLC**, Wallingford, PA (US)

(72) Inventor: **Joshua Epstein**, Wallingford, PA (US)

(73) Assignee: **SPROGO LLC**, Wallingford, CT (US)

(**) Term: **15 Years**

(21) Appl. No.: **29/770,441**

(22) Filed: **Feb. 12, 2021**

(51) **LOC (14) Cl.** **07-01**

(52) **U.S. Cl.**

USPC **D7/511**; D7/509; D7/510

(58) **Field of Classification Search**

USPC D7/300, 300.1, 392.1, 396.4, 507, 509, D7/510, 511, 523, 524, 532, 533, 534, D7/538, 624.1, 624.2, 624.3, 629; D9/449, 454

CPC A47G 19/2266; A47G 19/2272; A47G 19/2227; A47G 19/22; A47G 19/2288; A61J 9/00; B65D 43/0212; B65D 21/083

(57) **CLAIM**

The ornamental design for a beverage container assembly, as shown and described.

DESCRIPTION

FIG. 1 is a perspective view of the first embodiment of a beverage container assembly showing my new design;

FIG. 2 is a back view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a perspective view of the second embodiment of a beverage container assembly showing my new design;

FIG. 9 is a back view thereof;

FIG. 10 is a front view thereof;

FIG. 11 is a right side view thereof;

FIG. 12 is a left side view thereof;

FIG. 13 is a top view thereof; and,

FIG. 14 is a bottom view thereof.

1 Claim, 14 Drawing Sheets
